US00D540188S

(12) **United States Design Patent** (10) **Patent No.:** **US D540,188 S**
(45) **Date of Patent:** **** Apr. 10, 2007**

(54) **WIPES DISPENSING SYSTEM**

(76) Inventors: **Kurt Alfred Karussi**, 3450 Golden Ave. #16 KK, Cincinnati, OH (US) 45226; **Gregory deSwarte**, 5625 Eaglesridge La., Cincinnati, OH (US) 45230; **Yarron Bendor**, 9267 E. Chino Dr., Scottsdale, AZ (US) 85205; **Marcia Jo Cole-Yocom**, 3314 N. 85th Pl., Scottsdale, AZ (US) 85205; **Donna Marie Barker**, 5427 E. Fountain Cir., Mesa, AZ (US) 85205; **Allen Chandler Young**, 703 Oak Dr., Capitola, CA (US) 95010

(**) Term: **14 Years**

(21) Appl. No.: **29/244,615**

(22) Filed: **Dec. 12, 2005**

(51) **LOC (8) Cl. 09-01**

(52) **U.S. Cl. D9/734; D9/529**

(58) **Field of Classification Search D9/516, D9/518, 529, 541, 542, 559, 574, 730, 734; D6/512, 515, 518, 522, 523; 221/33, 45, 221/63, 64; 206/233, 494, 872; 220/200, 220/259.1**

See application file for complete search history.

(57) **CLAIM**

The ornamental design for a wipes dispensing system, as shown and described.

DESCRIPTION

FIG. 1 is an isometric view of the wipes dispensing system, embodying the new design;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines shown in the drawings are for illustrative purposes only and form no part of the claimed design.
